(57) **CLAIM**

The ornamental design for a housing for water heater, as shown and described.

DESCRIPTION

FIG. 1 is a perspective view of a housing for water heater;
FIG. 2 is a perspective view thereof;
FIG. 3 is a perspective view thereof;
FIG. 4 is a front view thereof;
FIG. 5 is a rear view thereof;
FIG. 6 is a left-side view thereof;
FIG. 7 is a right-side view thereof;
FIG. 8 is a top view thereof;
FIG. 9 is a bottom view thereof; and,
FIG. 10 is an enlarged partial view of a marked region in FIG. 1.

The broken lines are included for the purpose of illustrating the portions of the housing that form no part of the claimed design.
